WALDO SHELDON, OF SOUTH NORWALK, CONNECTICUT

WELL-DRILLING APPARATUS

Application filed May 5, 1926. Serial No. 106,850.

This invention relates particularly to oil well drilling apparatus of the type disclosed in prior pending applications wherein the feed of the drill is governed through the 5 operation of a power cylinder or cylinders. With these machines it has been the practice for the driller to watch the rotary table which turns the drill and to ease off the pressure or apply greater pressure as occasion requires. 10 This demands practically constant watchfulness and means that any lack of attention may result in injury or breakage of parts.

Special objects of the present invention are to automatically control the action of the 15 drill and to regulate the pressure so as to maintain the drill substantially continuously at the proper drilling speed.

Related objects are to enable the driller to arbitrarily control the drill independent- 20 ly of any automatic action and to enable the quick setting of the automatic control to different desired drilling speeds.

A further object of the invention is to 25 effect certain improvements in the hydraulic cylinder by which the pressure is applied to the drill stem.

The foregoing and other desired objects 30 are attained in this invention by certain novel features of construction, combination and re- lation of parts as hereinafter described and broadly claimed.

The drawings accompanying and forming 35 part of this specification illustrate a simple, practical embodiment of the invention, wherein:

Figure 1 is a side elevation and part dia- 40 grammatic view of the drill with automatic and hand control.

Figure 2 is cross sectional view of the pres- 45 sure feed valve.

Figure 3 is an enlarged part sectional view 50 of the hydraulic cylinder structure.

In Figure 1 the rotary table is shown at 5 driven by gearing 6 from shaft 7.

The hydraulic cylinder 8 is illustrated as 45 of annular construction concentrically sup- ported below the table. Figure 3 shows more in detail how this cylinder is made up of outer 55 and inner concentric walls 9, 10 forming be- tween them an annular chamber in which

operates the annular piston head 11 connect- ed with the upwardly extending annular pis- ton rod 12. This tubular piston rod through upwardly and downwardly acting thrust bearings 13, 14 can impart corresponding 55 movements to a drive sleeve 15 which is slid- ingly keyed in the table at 16 and carries clamping means indicated generally at 17 for gripping the drill pipe 18.

The piston head is shown as packed by a 60 plurality of substantially rectangular cross section rubber rings 19 seated in open recesses 20 at the opposite sides of the annular pis- ton and expanded by a pressure plate 21 of substantially U-shape cross section fitting 65 over the recessed sides of the piston head. This circular ring expander is shown as ad- justably secured by bolts 22 extending through the central part of the ring into the 70 central portion of the head, which bolts are accessible through ports 23 provided for the purpose in the lower annular cylinder head 24. These ports may be ordinarily closed by 75 plugs 25 and one or more of such ports may be utilized for entry of the power fluid by means of the lower pipe connection 26.

The upper cylinder head is shown as packed where the tubular piston rod emerges therefrom by similar elastic packing rings 27 supported in an open seat 28 at the inner 80 circumference of said head, the upper pack- ing ring being engaged by an expander 29 which can be forced down by a screw ring 30. To further seal the piston in the cylin- 85 der, packing rings are shown at 31 inter- posed between the inside of the annular pis- ton rod and the inner cylinder wall 10. The power fluid is entered into the top of the cylinder above the piston head through a 90 connection 32.

It will be evident from the foregoing that by controlling admission and exhaust of the power fluid through piping 26 and 32, pres- 95 sure may be applied to raise and lower the drill stem without in any way interfering with the rotation of the drill stem by the table.

Water under pressure is employed as the power fluid in the present disclosure and the control is shown as effected by a special 100

valve indicated generally at 33 in Figure 1.

This valve is illustrated in detail in Figure 2 as a casing having an inlet port 34 between two piston valves 35, 36 controlling flow through ports 37, 38 to the upper and lower supply pipes 32, 26. The valve casing also has an exhaust port 39 from which return piping 40 extends to a supply tank 41. A pump is indicated at 42 for taking water from this tank through piping 43, the pressure side of the pump being connected by piping 44 with the supply port 34 of the valve.

The piston valves 35, 36 of the control mechanism are shown connected by a stem 45 which is engaged at 46 with one end of a hand lever 47 pivoted at 48. It will be seen that by raising this hand lever the valve stem 45 will be lowered to admit pressure from port 34 past piston valve 36 to port 38 and through piping 26 to the lower end of the power cylinder, and conversely, that the lowering of the hand lever will lift the valve stem to open port 37 and admit pressure to the top of the power cylinder. Consequently, the power piston and hence the drill pipe gripped in the drive sleeve connected with said piston will be raised and lowered as the hand lever 47 is raised and lowered.

30 A scale and pointer mechanism 49 is indicated at the end of the hand lever to gage the adjustments and a hand screw is shown at 50 engaged on a screw stem 51 connected with the lever and extending through a 35 guide 52 which enables the hand lever to be set at any desired adjustment.

By means of the control valve it will be seen that the driller can raise or lower the drill bit at will. Usually, the operation of 40 the turntable is observed and if it slows down, due to the bit encountering a harder stratum, the drill is lifted to relieve the weight on the bit and conversely, if the table speeds up, pressure is applied to increase the 45 load and bring the table back to the proper drilling speed. This control requires the constant attention of the driller, is uncertain and always involves a certain amount of "lag" between the time when the change actually occurs and the time when the driller 50 after noticing the change has had opportunity to apply corrective measures. These uncertainties and delays are eliminated in the present invention by automatically governing the pressure applying mechanism 55 from the speed of rotation of the shafting which drives the table.

In the present disclosure the automatic governor is shown as a ball governor 53 driven from the sprocket gearing 54 and bevel gearing 55 from the main drive shaft. This governor is shown as having its movable collar 56 revolvably connected with an upright link 57 which in turn is connected 60 with the hand lever of the control valve.

The connection with the hand lever is shown as made by means of a hand nut 58 engaged on a screw stem 59 carried by the lever, the link being slotted at 60 so that it may either slide freely over the screw stem or else be clamped rigidly to the hand lever by means of the hand screw.

With the hand screw loosened it will be seen that the hand lever of the control valve may be raised and lowered free of any control from the governor. With the hand screw tightened, however, it will be clear that the hand lever will be shifted by the governor

and the application of the raising and lowering power be thereby given over to the automatic governor. With the proper drilling speed known, the control handle may be set to provide the drilling force suited to that particular speed and the governor be then placed in control for that speed by simply turning the hand screw to clamp the connecting link to the hand lever. The governor thus placed in control senses any changes in speed in the drive shaft before they would be perceptible to the driller and operates immediately to offset the result of such changes and to restore the rotary at once to the speed of operation for which the control has been set.

The slowing down of the governor causes the balls to approach the center and to lift the movable collar to which they are connected. A corresponding lift is thereby imparted to the hand lever through the medium of the releasable connecting link. As the balls fly apart with an increase in speed, the collar is lowered and the hand lever is correspondingly lowered. Hence if the table starts to slow down, the control valve is operated to lift the drill and if the table starts to speed up, the control valve is operated to lower or to apply more pressure to the drill.

Thus in both instances the turntable is quickly and almost immediately brought back to the predetermined desired drilling speed, making the machine more effective, faster in operation and at the same time protecting the drill bit and pipe from overstrain. If desired, a speedometer or revolution counter may be applied to the drive shaft so that the driller may know exactly at what speed 115 the drive shaft and table are turning and set the automatic control accordingly.

To allow an automatic normal rate of feed of the drill, the control valve is shown provided with a "bleed" 61 arranged to permit the power fluid to slowly escape from the lower end of the cylinder and hence to permit the piston to automatically sink at a predetermined slow rate, such rate depending upon the position at which the lower valve member is left by the control handle. Thus there is provided, in addition to the means for maintaining the rotary table at a predetermined drilling speed, means for automatically feeding the drill at a prede-

terminated normal drilling speed. The driller may therefore set the machine for a certain desired normal rate of feed and then rely on the governor to take care of any abnormal or unusual formations and to return the drill back to the normal feed after the formation changes have been countered and taken care of.

What is claimed is:

10. 1. In well drilling apparatus, a table for rotating the drill, hydraulic power mechanism for controlling feed of the drill, a control valve for said hydraulic power mechanism and a speed governor associated with the table and adapted to exercise control over said valve. 75
15. 2. In well drilling apparatus, a table for rotating the drill, hydraulic power mechanism for controlling feed of the drill, a control valve for said hydraulic power mechanism and a speed governor associated with the table and adapted to exercise control over said valve, said governor being connectible with the valve in different relative 80
20. 25. 3. In well drilling apparatus, a rotary table, a power cylinder, connections actuated thereby for applying the lifting and lowering forces of said cylinder to a drill rotated by the table, a control valve operable to govern the effect of said power cylinder and automatic means dependent on the speed of operation of the table for automatically controlling said valve. 85
30. 35. 4. In well drilling apparatus, a rotary table, a power cylinder, connections actuated thereby for applying the lifting and lowering forces of said cylinder to a drill rotated by the table, a control valve operable to govern the effect of said power cylinder and automatic means dependent on the speed of operation of the table for automatically controlling said valve, said control valve having means which can be set to enable the 90
40. 45. 5. In well drilling apparatus, means for rotating a drill stem, hydraulic power mechanism for feeding the drill stem, valve means for governing said hydraulic feed mechanism and means dependent on the speed of rotation of the drill stem for automatically actuating said valve means. 95
50. 6. In well drilling apparatus, means for rotating a drill stem, hydraulic power mechanism for feeding the drill stem, valve means for governing said hydraulic feed mechanism and means dependent on the speed of rotation of the drill stem for automatically actuating said valve means, said valve means having 100
55. 65. mechanism for enabling a predetermined feed of the drill, independently of the automatic control. 105
7. In well drilling apparatus, means for rotating a drill stem, hydraulic power mechanism for feeding the drill stem, valve means for governing said hydraulic feed mechanism and means dependent on the speed of rotation of the drill stem for automatically actuating said valve means, said valve means being readily disconnectible from said automatic 110
- control means. 115
8. In well drilling apparatus, means for rotating a drill stem, hydraulic power mechanism for feeding the drill stem, valve means for governing said hydraulic feed mechanism and means dependent on the speed of rotation of the drill stem for automatically actuating said valve means, said valve means having a manually operable control and means for coupling the automatic control to said manual 120
- control in different selected positions of the manual control. 125
9. In well drilling apparatus, a rotary table, shafting for driving the same, a speed governor driven from said shafting, a control valve actuatable by said governor, a power cylinder for regulating feed of a drill stem rotated by the table and power connections from said valve to said power cylinder. 130
10. In well drilling apparatus, a rotary table, shafting for driving the same, a speed governor driven from said shafting, a control valve actuatable by said governor, a power cylinder for regulating feed of a drill stem rotated by the table and power connections from said valve to said power cylinder, said control valve having means for automatically effecting a predetermined feeding operation of the power cylinder. 135
11. In a well drilling apparatus, a rotary table, shafting for driving the same, a speed governor driven from said shafting, a control valve actuatable by said governor, a power cylinder for regulating feed of a drill stem rotated by the table, power connections from said valve to said power cylinder, said control valve having means for automatically effecting a predetermined feeding operation of the power cylinder and said control valve being readily disconnectible from said governor. 140
12. In well drilling apparatus, a rotary table, shafting for driving the same, a speed governor driven from said shafting, a control valve actuatable by said governor, a power cylinder for regulating feed of a drill stem rotated by the table, power connections from said valve to said power cylinder, said control valve having means for automatically effecting a predetermined feeding operation of the power cylinder and means for connecting the governor and control valve in various different relations of the two. 145
13. In well drilling apparatus, a rotary table, shafting for driving the same, a speed 150

- governor driven from said shafting, a control valve actuatable by said governor, a power cylinder for regulating feed of a drill stem rotated by the table, power connections from said valve to said power cylinder, said control valve having means for automatically effecting a predetermined feeding operation of the power cylinder, means for connecting the governor and control valve in various different relations of the two, and an indicator for gaging the relation of said parts with the rotary table for assisting in the coupling of the governor at the desired speed relation.
14. In well drilling apparatus, the combination with a rotary table and a power cylinder operable to variably feed the drill rotated by the table, of control means for said power feed mechanism adjustable to set the power mechanism for a predetermined "normal" rate of drill feed and an automatic device governed by the speed of rotation of the table and operable on the control means to cause the latter to effect slower or faster feed or return to normal feed in accordance with the formation encountered.
15. In well drilling apparatus, a rotary table, a power cylinder, connections actuated thereby for applying the lifting and lowering forces of said cylinder to a drill rotated by the table, a control valve operable to govern the effect of said power cylinder, and automatic means governed by the speed of rotation of the drill rotated by the table and connected with the valve to exercise control over said valve and to thereby govern the drill lifting and lowering effect of the power cylinder.
16. In a well drilling apparatus, the combination with a rotary table and a power cylinder for variably feeding a drill rotated by the table, of control means for said power feed mechanism and a speed governor associated with the table so as to rotate in accordance with the speed of the table rotation, said speed governor being connected to effect operation of said control means and thereby cause the power mechanism to variably feed the control according to the speed of rotation of the table.
17. In well drilling apparatus, the combination with a rotary table and a power cylinder for variably feeding a drill rotated by the table, of control means for said power feed mechanism adjustable to set the power mechanism for a predetermined "normal" rate of drill feed and an automatic power governor dependent for its operation upon the speed of rotation of the drill by the table, said governor being connected with the control means for advancing the setting of the same beyond that for the "normal" predetermined rate of drill feed to thereby advance the drill faster than permitted under the setting for "normal" feed when formation conditions en-

countered by the drill warrant faster feeding than what the control means is first set for.

In witness whereof, I have hereunto set my hand this 30th day of January, 1926.
